UNITED STATES PATENT OFFICE.

THOMAS BARDON AND CHARLES E. WIBERG, OF ASHLAND, WISCONSIN.

CULVERT.

No. 828,917.

Specification of Letters Patent.

Patented Aug. 21, 1906.

Application filed December 6, 1905. Serial No. 290,526.

To all whom it may concern:

Be it known that we, THOMAS BARDON and CHARLES E. WIBERG, citizens of the United States, residing in Ashland, in the county of 5 Ashland and State of Wisconsin, have invented certain new and useful Improvements in Culverts, of which the following is a specification, reference being had to the accompanying drawings.

10 Our invention relates to improvements in culverts made up of three or more parts or sides assembled together; and the object of our invention is to provide a culvert of this class which will be readily assembled, strong 15 to resist pressure, non-collapsible, and provided with means for securing to it branch pipes, as the branch pipes used by abutters in case the culvert is a sewer-pipe laid along a city street, for example.

20 A culvert of the class just referred to and now in common use is one in which the sides are formed with alternate lugs and notches, the lugs of one side fitting into the notches of the sides thereto adjacent. These lugs project from the edges of the sides and under pressure from the outside they frequently break off, in which case the culvert collapses, since there is no support for the side after the lugs have broken off, and one lug's breaking 25 results in the stress being thrown entirely upon the remaining lugs, with the result that they break off in succession. To prevent this collapse of the culvert and to give support in case the lugs break, as described, we 30 provide the sides with a thickened edge, against which the side or edge of the adjacent plate abuts and upon which it rests and is supported in case the lugs give way. In 35 case of the bottom plate the two longitudinal 40 sides may be thickened.

In case the culvert referred to above as being in common use now is subjected to great pressure from within, the lugs tend to slip out of the retaining-notches, thereby wrecking 45 the culvert as a whole. To prevent this untoward result, we provide the lugs or flanges with inwardly-projecting ears or teeth which pass upon the outside of the adjacent plate or side. In this way we supply means for resisting pressure from within the culvert—as, 50 for instance, the pressure due to the formation of ice in the culvert.

The culvert above referred to as being in common use is connected with the small 55 pipes of users or abutters by means of brick

arches or chambers. To provide means for directly attaching the small pipes of such users, we form some of the plates or sides of our culvert with an opening about which is an outwardly-projecting collar. The small 60 pipes of the users slip over this collar in much the same way as a piece of stovepipe slips over the ring formed upon the ordinary range for its reception.

The culvert above referred to as being in 65 common use is made up of plates which form a side by having their ends abut one against the other. In case the earth settles unevenly it frequently happens that the sections pull apart from each other, resulting in the dismantling of the culvert. To prevent this, 70 the sides are provided with a flange at the end which overlaps the abutting end of the next plate or section, which is adapted to fit inside the flange.

75 In the drawings illustrating the principle of our invention and the best mode now known to us of applying that principle, Figure 1 is a perspective view of our new culvert. Fig. 2 is a sectional view upon the line A A of 80 Fig. 1, and Fig. 3 is a transverse sectional view showing a modification.

The bottom plate *a* becomes gradually thicker from its longitudinal mid-line toward its longitudinal edges *b b*, and from these 85 edges *b* project a series of lugs *c* of a less thickness than the edge *b*, whereby a shoulder is left, as at *d*, Fig. 3. Upon each of the lugs *c* is formed an inwardly-projecting tooth *e*, within which fits the edge of the side *f*, the lugs *c* of which interlock between the lugs *c* of the sides *a* and *g* and are formed with teeth *e*, as in the case of the bottom plate *a*. The plate *f* thickens from its lower edge to its upper edge, as is clearly shown in Fig. 1, and 90 it is formed with openings *h*, around which there is a raised collar *i* to form a neck, within which slips the pipe which connects the culvert with houses which it serves as a main sewer. The side *g* increases in thickness 95 from its lower to its upper longitudinal edge and is formed with toothed lugs *c*, which interlock with the lugs upon the plates *a* and *f*.

The several plates *a*, *f*, and *g* are formed with flanges *j*, which overlap the abutting 100 ends of the corresponding plate of the succeeding section of the culvert, as is clearly shown in Fig. 2. These flanges *j* not only provide for an accurate fitting of the sections one within the other, but also prevent the 105

plates from falling apart in case the earth settles unevenly, which frequently occurs. The ribs *k* serve to strengthen the plates.

In Fig. 3 a modification is shown differing from the preferred form shown in Fig. 1 in only one respect—to wit, the plates *a'*, *f'*, and *g'* are each thickened toward one edge. It will be apparent to all skilled in this art that in any case the side plates can be thickened only along one longitudinal edge, while the bottom plate may be thickened along both longitudinal edges, as shown in Fig. 1.

We are aware of the patents granted F. S. and F. H. Beach, March 10, 1903, No. 722,396, and A. Lauridtzen, December 8, 1903, No. 746,112, and disclaim all that is therein shown.

What we claim is—

1. A culvert made up of a plurality of interlocking plates each of which is formed with lugs which project outwardly from the longitudinal edges of the plate, the lugs of one plate entering between the lugs of the two adjacent plates in interlocking engagement therewith; one of said longitudinal edges in each plate being continuous and thickened, and formed integral with the plate itself, the thickness of said thickened longitudinal edge being greater than that of the lugs which project outwardly therefrom, whereby a supporting-shoulder is formed on the inner wall of each plate along said thickened longitudinal edge.
2. A culvert made up of a plurality of in-

terlocking plates formed with lugs which project from their longitudinal edges, the lugs of one plate entering between the lugs of the two adjacent plates to interlock therewith; said plates being formed with a continuous thickened longitudinal edge, the lugs projecting from said edge being of less thickness than said edge, whereby a supporting-shoulder is formed along said edge; said lugs being formed with an inwardly-projecting tooth between which and said shoulder the edge of the adjacent plate is seated; said teeth resisting pressure from within the culvert.

3. A built-up culvert made up of a plurality of interlocking plates having thickened longitudinal edges from which project lugs of less thickness than said edge, whereby a supporting-shoulder is formed along said edges; said lugs being formed with teeth in the groove between which and said shoulder the edge of the adjacent plate is seated; said plates being provided with flanges at one end which overlap the abutting end of the corresponding plate of the next succeeding section of the culvert; and a side plate of said culvert being formed with an opening having a raised collar therearound for the connection of a house-pipe.
